FIG. 1 is a perspective view of a spring seat showing my new design.

FIG. 2 is a front elevational view of the spring seat.

FIG. 3 is a back elevational view of the spring seat.

FIG. 4 is a top view of the spring seat.

FIG. 5 is a bottom view of the spring seat; and,

FIG. 6 is a right side view of the spring seat, the left side view being a mirror image of this view.

The broken line depictions of the raised portion of the top of the spring seat and bolts in FIGS. 1-6 are for illustrative purposes only and form no part of the claimed design.
